UNITED STATES PATENT OFFICE

KARL VOLLMAND, OF CASSEL, GERMANY, ASSIGNOR TO THE SUPERHEATER COMPANY, OF NEW YORK, N. Y.

SUPERHEATER HEADER

Application filed May 11, 1929, Serial No. 362,168, and in Germany June 23, 1928.

The subject matter of this invention is a superheater consisting of two separate parts. Superheaters of this kind have the advantage that they can be readily fabricated as simple castings or in some other manner and that by doing so strains from casting and from temperature differences are avoided and that in addition an interchange of heat between the chamber containing the superheated steam and the one containing the saturated steam is avoided.

On account of its peculiar form a steam header made in accordance with this invention has additional important advantages inasmuch as it may be used both for superheaters in boilers with enlarged flues and for superheaters in normal diametered flues.

In cases where the flues are of enlarged diameter and particularly where the flues are staggered it becomes impossible, if the diameter of the flues exceeds a certain amount, to accommodate the element ends side by side in the usual manner because with such larger diameters of the flues the space between adjacent flue rows is insufficient for the flanges necessary to secure said ends.

In the case of superheaters located in flues of normal diameter especially where the boiler is designed for high ratings and, therefore, is equipped for a large number of such flues, care must be taken to keep the elements as simple as possible and to keep the number of joints and clamps as small as possible since it is difficult to find space on the headers for the large number of superheater element ends. In addition, care must be exercised, that with the very large number of the superheater elements which have to be secured, the dimensions of the steam headers do not exceed the normal size, so that the diameter or length of the smoke boxes does not have to be increased.

These difficulties are obviated if a steam header in accordance with the present invention is used, this being accomplished by giv-

ing to the steam header a middle chamber and two chambers separated from it and adjoining it laterally, the latter two chambers being connected to each other. The connection of these two lateral chambers may be accomplished by means of bridging pieces which are either unitary with the lateral chambers or are fabricated separately and subsequently connected to these chambers. The central chamber is therefore, surrounded by the two U-shaped lateral chambers with their connecting pieces.

According to one form of the invention the latter chambers are so shaped that they form a frame-like structure which surrounds the center chamber and all four sides. With this form of the outer chambers the possibility is presented to secure the inner chamber with the outer frame-like chamber in a very simple manner. This is done by means of wedges and set-screws which act on flanges formed on adjacent walls of the chambers.

In the case of smoke tube superheaters located in flues of enlarged diameter the form of the steam header, according to the present invention presents the possibilities, especially when the flues are staggered, to retain superheater elements of simple form and extending into single flues and yet connecting their wet and superheated ends to the header in such a manner that the wet and superheated ends of each element are arranged in front of each other looking at them in the direction of the longitudinal axis of the boiler. This removes the difficulties ordinarily encountered in finding space for connecting the superheater element ends to the steam chambers.

In the case of the superheaters in flues of normal diameter the superheater elements associated with any given tier of flues can be grouped into two independent groups lying in a single plane, one in front of the other and the ends of these groups can be secured to the lower side of the steam header in such

a way that for each group the wet and superheated ends and their points of attachment to the header lie in single plane in front of each other in such a manner that two like element ends are in the center. In addition to the compact arrangement and the small fore-and-aft length of the header, the advantage is secured that the means used to hold the ends to the steam chamber engage only like ends and therefore no leaks result from unequal expansion of the ends.

The drawings show views illustrating different forms of the invention. Figs. 1 to 3 show a steam header applied to a superheater located in flues of normal diameter. Fig. 1 shows a front view of the superheater viewed from the smoke box, Fig. 2 is a longitudinal section on line 1—1 of Fig. 1, and Fig. 3 shows a top view of the steam header. Figs. 4, 5 and 6 show views, corresponding respectively to Figs. 1, 2 and 3, of another form of the superheater header applied to a superheater whose units extend into enlarged flues. Whereas the first two forms show a steam header having bridging pieces between the front and rear chambers, Figs. 7 to 11 represent a so-called frame header. Figs. 7 to 9 illustrate in three views corresponding to those of Figs. 4 to 6, a superheater in enlarged flues, while Figs. 10 and 11 show a modification of this form. Fig. 12 illustrates the manner in which the central chamber is connected to the outer frame chamber.

In the form of the invention illustrated in the Figs. 1 to 3 all smoke tubes 1 are occupied by superheater elements 2 which are so arranged that the superheater elements belonging to any vertical row of flues are gathered into two groups A and B which lie one in front of the other in the plane of the row of flues. In each case three superheated and three saturated ends are connected by means of the intermediate chambers 3 which are secured to the lower side of the header 4 by means of clamps 5 and the central bolts 6, in such a manner that in each group of elements the saturated and superheated ends and their points of attachment and means of attachment lie one in front of the other in the same plane. A common clamp 5 therefore, engages only like elements, that is, either wet steam ends or superheated steam ends. The steam header 4 comprises a central superheated steam chamber 7 which is surrounded by the U-shaped saturated steam chambers. The latter comprises two lateral chambers 8 which are connected to each other by means of the bridging piece 9. Saturated steam is carried to the header by means of the connection 10 while the superheated steam leaves for the engine through the pipes 11. The central chamber 7 of the steam header 4 can, therefore, be fabricated separately as may also be the lateral chambers 8. The connecting bridge 9 can be made unitary with the

two chambers 8 or secured to them subsequently.

The advantages of a steam header corresponding to this invention are obtained not only when the header is placed in the upper part of the smoke box as in the example described, but also if the header is placed at the sides or in the lower part of the smoke box. Moreover, the saturated steam can be carried to the middle chamber 7 in which case the outer chambers 8 would be superheated chambers. In the form illustrated, the bolts 6 are given the form of studs and are screwed into the lower walls of the headers. In Figs. 4 to 6 there is illustrated another form of the header applied to a large tube superheater, the bolts 6 here extending through the header. For this purpose the lateral and inner chambers are arranged at a greater distance from each other so that these bolts may readily be inserted and their longitudinal walls are provided with surfaces to be engaged by the nuts of the bolts 6. Each pair of saturated and superheated steam ends 13, 14 are engaged by the clamp 3 which is secured to the steam header by means of the central bolt 6. The superheated steam is carried away by means of the two lateral pipes 11. In other respects the arrangement is the same as that of the first example. The advantage is here also present that the ends and the means of securing them to the header can be accommodated without elongating the header in the longitudinal direction of the smoke box.

In the header corresponding to Figs. 7 to 12, the lateral chambers 8 are given the shape of a frame-like housing surrounding the central chamber 7 on all sides (see Figs. 9 and 10). Figs. 7 to 9 show the use of this header in connection with a superheater in enlarged flues, the central chamber 7 being the saturated chamber while in the form of Figs. 10 and 11 the central chamber 7 is the superheated chamber. The outer frame-like chamber 8 rests by means of its flanges 15 on the brackets 16 in the smoke box and the central chamber 7 is clamped to the frame-like chamber 8. For the latter purpose, the two adjacent walls of the two chambers are equipped with upwardly extending flanges 17 which are connected to each other by means of the wedge 18 and the setscrew 19.

I claim:

1. In a superheater header the combination of three parallel elongated chambers, the central one being entirely separate from the other two, bridging channels connecting the ends of the other two and extending opposite the ends of the central chamber, flanges extending upward from the channels and from the ends of said first chamber, juxtaposed faces of said flanges being grooved, keys engaging said grooves, and set screws engaging said keys.

2. In a locomotive superheater header the combination of three parallel elongated chambers with flat lower faces lying in a common plane, the central one being entirely separate from the other two, the outer two being connected by bridging channels extending across the ends of the central chamber, means to connect a pipe to the central header, means to connect a pipe to the outer headers, and
10 means adjustably to hold the chambers in their relative position.

KARL VOLAND.
